Application May 31, 1941, Serial No. 395,955
In Japan December 19, 1939

16 Claims. (Cl. 219—40)

This invention relates to a device for heating a liquid, such as water, by electricity. The heating may be for the purpose of providing hot water, as for domestic consumption, or it may be for the purpose of generating steam or vapor, or the like.

Numerous devices have been proposed and used for such purpose or purposes. In some of these, the heating current has been passed directly through the liquid, spaced carbon elements immersed in the liquid serving to conduct the current to and from the liquid.

It has been found that in this type of heater, the electrodes are soon coated with deposits, especially when the usual city water is the liquid that is being treated. The resultant necessity for frequent repairs and replacements is a serious disadvantage of this kind of heater.

It is an object of this invention to provide a heater wherein the electrodes are so arranged that after initial vaporization of the liquid, an arc discharge is formed through the vapor, the heat of the arc serving to heat and vaporize the incoming liquid.

It is another object of this invention to provide an electrical heater of the type using submerged elements, so arranged as to prevent deposition of solid matter on the elements.

It is still another object of this invention to provide such a heater wherein the incoming liquid is caused to pass about the outside of annularly arranged elements to absorb such heat as may pass through an outer electrode and prevent its loss through radiation by the body of the heater.

It is still another object of this invention to provide a heater comprising means whereby a small flow of liquid through the heater, as by accident, will be prevented from activating the heating elements.

It is a still further object of this invention to provide a heater having an improved arrangement of terminals for the heating elements, whereby arcing between the terminals is prevented.

It is a still further object of this invention to provide an instantaneous water heater for lavatories or the like of simple and durable design and easy of installation.

This invention possesses many other advantages, and has other objects which may be made more easily apparent from a consideration of several embodiments of the invention. For this purpose there are shown a few forms in the drawings accompanying and forming part of the pres-

ent specification. These forms will now be described in detail, illustrating the general principles of the invention; but it is to be understood that this detailed description is not to be taken in a limiting sense, since the scope of the invention is best defined by the appended claims.

In the drawings:

Figure 1 is a longitudinal sectional view of a lavatory heater embodying the invention;

10 Fig. 2 is a sectional view, taken along plane 2—2 of Fig. 1;

Figs. 3 and 4 are fragmentary longitudinal sectional views, as taken along correspondingly numbered planes of Fig. 2;

15 Fig. 5 is a longitudinal sectional view, taken along plane 5—5 of Fig. 1;

Fig. 6 is a cross sectional view, taken along plane 6—6 of Fig. 5;

20 Fig. 7 is a fragmentary sectional view, taken in the plane of Fig. 1, showing a terminal structure used in connection with the invention;

Fig. 8 is a section as seen on plane 8—8 of Fig. 7;

25 Fig. 9 is an elevation of the underside of another terminal structure used in connection with the invention;

Fig. 10 is a side elevation of the structure of Fig. 9;

30 Fig. 11 is a side elevation of the connector used with the terminal structures;

Fig. 12 is a top plan view thereof;

Fig. 13 is a side elevation of the cover for the body;

Fig. 14 is a view of the underside thereof;

35 Fig. 15 is a side elevation of the cap for the outside heating element;

Fig. 16 is a bottom plan view thereof;

Fig. 17 is an elevation of a modified form of the invention;

40 Fig. 18 is a similar view, partly in section;

Fig. 19 is a top plan view of the structure of Fig. 18; and

Fig. 20 is a fragmentary transverse section as seen on plane 20—20 of Fig. 19.

45 In that form of the invention illustrated in Figs. 1 to 16, a compact instantaneous water heater for lavatory purposes is disclosed. Therein, a pair of cylindrical electrodes, 1 and 2, of suitable material such as carbon, are nested concentrically within an enclosing housing or casting 3. The housing 3 and electrodes 1, 2, cooperate to define narrow vertical annular spaces 4, 5 for the passage of the liquid to be heated and are mounted on a base 6. The base 6 as will be more

55 fully described later, comprises various passage-

ways by which liquid is permitted to flow from inlet 7 to the discharge spout 8. The passage of this liquid is controlled by valves or faucets 9, 10. One of these valves, as 9, serves to control the flow directly from inlet 7 to spout 8, while the other valve 10, serves to admit liquid to the annular spaces 4, 5, where it is heated, before passing to spout 8. By appropriately adjusting the openings of valves 9, 10, the temperature of the discharged liquid may be varied as desired.

The arrangement is such that the annular space 4, between elements 1 and 2 is relatively very narrow. Thus, the liquid entering this space passes between the electrodes in a thin sheet through which the current passes between the electrodes in the form of a multitude of arc discharges. These heat the passing liquid and may even vaporize a portion of it.

By appropriate choice of the space 4 between the electrodes 1 and 2, it is possible to produce heating effects other than that caused directly by the electrical energy expended. Apparently there is a breakdown, by the arc, of atoms of the constituents of the liquid, releasing additional heat, and giving a total heat output greater than that represented by the expenditure of the electrical energy. Although no very specific rule can be stated for the separation of the electrodes 1 and 2 for securing these results, it has been found that this separation should be about .045 inch when a 220 volt circuit is utilized. However, the character of the water has some effect upon optimum spacing, it having been found that the harder the water, the farther apart the electrodes may be spaced.

By reducing the flow in accordance with the area of the electrodes, it is possible to ensure complete vaporization, but such is obviously not desirable in the embodiment under discussion. By arranging that the liquid flows downwardly between the electrodes, any solid matter tending to be deposited on the electrodes will be washed downwardly and out the discharge, together with any miscellaneous material carried by the liquid. Thus, any tendency of the heater to "lime up" is obviated.

Referring in more detail to the structure, the cylindrical carbon electrodes 1 and 2 are supported concentrically about a vertical axis 11 by means of the hollow body 3, which is made of insulation material capable of withstanding the temperatures attained. Such material may be Bakelite, porcelain, a plastic product, or the like. This body 3 has an internal cylindrical space or cavity 13 coaxial with axis 11, is provided with a flange or wall 14 at its lower end, having an annular recess 15 therein. This recess 15 forms a shoulder 16 at the bottom of cavity 13, as well as a shoulder 17 around the integral tubular extension 18 formed within body 3. These shoulders 16 and 17 form supporting surfaces for electrodes 2 and 1 respectively. In order to give increased strength to extension 18 it is made of tapering configuration so as to have an increased cross section adjacent its point of attachment 19 to wall 14.

A tubular member 21 of copper or other good conducting material closely embraces the outer electrode 2 and is in good electrical contact therewith. This member 21 serves to maintain the 70 electrode 2 coaxial with respect to cavity 13 in body 3 as well as with electrode 2, as will be presently described. Current for the electrode is supplied by a suitable connection to member 21.

Similarly, the inner electrode 1 is in good elec-

trical contact with a copper tube 22 accommodated in a central tapered bore 23. Bore 23 is of such size and taper that when electrode 1 is resting on seat 17, the electrode 1 is held axially by stem 18.

The terminal structures for the inner and outer electrodes 1 and 2 are clearly shown in Figs. 1, 3 and 7 to 12. Thus at the upper end of tube 22 of the inner electrode 1 a metallic terminal flange 24 (see Figs. 9 and 10) is telescoped over the tube. This collar 24 has a wide radial extension 25 for the accommodation of a screw 26 to which is secured the terminal collar 27.

The terminal structure for the outer electrode 15 2 includes a flanged metallic ring 28 telescoped within the upper end of the tubular member 21 (see Figs. 7 and 8). This ring 28 has an inwardly directed extension 29 for accommodating a screw 30 38 to which is secured a terminal collar 31, similar to collar 27. A portion of ring 28 opposite extension 29 is omitted, to provide appropriate clearance for the terminal flange 24 of the inner electrode 1.

As shown most clearly in Figs. 1, 3, 15 and 16, a cover 35 of suitable insulating material extends over electrodes 1 and 2, and the annular space 4 between them. This cover has a central aperture 36 for accommodating tube 22 and stem 18. Aperture 36 is a close fit over tube 22. Cover 35 has a depending flange 37, the lower face of which contacts the top of electrode, and the periphery of which closely fits within tubular member 21. By this arrangement, member 21 and the outer electrode 2 are maintained coaxial with stem 18, and hence with electrode 1. To permit communication between the annular spaces 4 and 5 it is provided with a number of cutaway portions 38 which are aligned with openings 39 in member 21 during assembly.

40 A spacer or separator 41 is mounted on cover 35 and within flanged ring 28, a suitable resilient gasket 42 being interposed between them. Separator 41 fits snugly within ring 28 and has a central aperture 43 for accommodating the upper end of stem 18, as well as a recessed portion 44 on its lower surface for accommodating terminal lug 24. The purpose of separator 41 is to effectively isolate the terminal structure 24-25-26-27 of electrode 1 from the terminal structure 50 28-29-30-31 of electrode 2, to ensure against arcing between them.

The assembly is made fluid tight by means of a resilient ring gasket 58 disposed on a shoulder 51 formed about the top of annular space 18. Gasket 58 is substantially on a level with gasket 42 and has a central opening 52 for accommodating ring 28. Above gasket 58 is a cap 53 (see also Figs. 13 and 14), formed of suitable insulating material. The under surface of cap 53 is provided with a recess 54 for accommodating ring 28 and separator 41, and a central depression 55 for receiving the upper end of stem 18, as well as a through hole 56 for accommodating a long stud 57 which extends axially of stem 18. Stud 57 is secured in base 6 as by having its lower end threaded therein, a nut 58 threaded on the upper portion of the stud engaging the upper surface of the cap 53, a suitable washer 59 being interposed. By means of stud 57, nut 58, etc. cap 53 may be clamped downwardly against gasket 58, spacer 41 and gasket 42. A gasket 60 may also be provided between the top of stem 18 and the bottom of recess 55. Further, this clamping is also effective to tightly secure body 3 to the base 6.

Cap 53 is provided with recesses 63 and 64 in its upper surface to receive terminal collars 27 and 31, as well as the leads thereto. Holes 85 and 86 (Fig. 14) extend through the cap from recesses 63 and 64 respectively into recesses 54 for accommodating screws 26, 30, as the case may be. A circular cover plate 89 is secured on top of cap 53, as by screws 70, to cover recesses 63 and 64.

As clearly shown in Figs. 1, 3, 11 and 12, each of the terminal collars 27, 31 comprises a cylindrical body 73 having a threaded axial bore 74 extending through it. This bore 74 is of two diameters, the portion of smaller diameter being to receive the mounting screw, 26, 30. The portion of larger diameter has a headless set screw 75 threaded therein. This portion of the bore is intersected by a radial slot 76. The conductors 79, 80 are clamped respectively between the bottoms of bores 74 and set screws 75, being inserted into the bore through slots 76. These conductors pass forwardly and downwardly of body 3, through apertures 81 into base member 6, whence they may lead to an appropriate source of electrical energy.

In order to present a smooth, finished appearance, a metallic domed cover 84 (Figs. 1, 3, 5 and 6) may be provided. This cover 84 closely embraces the rear and side portions of body 3 (see Fig. 6) but is swelled out in front as indicated by 85 to accommodate leads 79, 80. The lower edge of cover 84 rests on the upper surface of base member 6, which is shaped to conform therewith. Cover 84 is held in place by the aid of a screw 86, passing through the top of cover 84 into a threaded aperture formed in the upper portion of stud 57.

Body 3 may if desired have a protective sleeve 87 of metal or the like, for purposes of reenforcement, over which cover 84 is telescoped.

Water or other liquid to be heated is supplied to the annular space 4 through an opening 90 (Figs. 1 and 2) formed in body 3 and extending downwardly through a boss 91 on the bottom of body 3. The base or supporting member 6 has an aperture 92 into which boss 91 extends. A sealing gasket 93 accommodated in a recess 94 in the bottom of body 3, provides a fluid tight connection. Thus, port 90 connects with a passage 95 formed in base 6 and leading to a control valve or faucet structure 10 to be presently described.

The water is forced upwardly, by the pressure of the source of supply, into annular space 5 about the outer electrode 2, absorbing heat therefrom that would otherwise be radiated by the body and wasted. The water then passes through openings 38, 39 into the annular space 4 between the electrodes 1 and 2, where it passes downwardly, being heated by the action of the arc formed between these electrodes as before mentioned. The heated water then passes into the annular space 15 (Figs. 1 and 4) formed in the bottom of body 3. Thence it proceeds through port 98 (Figs. 2 and 4) into a passage 99 and is discharged through a spout 8 formed integrally with base 6. Port 98 extends through a boss 101, similar to boss 91 and maintained in fluid tight relation to base 6 in the same way.

The means for supplying water to the intake passage 95 may now be set forth. Base member 6 has a downwardly extending integral post 102 (Figs. 1, 4 and 5) with a threaded extremity. Through it extends a water inlet passage 103 communicating with supply pipe 7, joined in a

conventional fluid tight manner to the end of post 102. Furthermore, this post 102 may be arranged to pass through a hollow metal casing member 105, disposed on the bottom surface of a supporting wall 107. This supporting wall 107 may represent a portion of a wash basin or the like with which the device is adapted to cooperate. A gasket 108 may be disposed in a suitable recess 106 in the lower edge of a flange 109 formed integrally with base member 6, and in contact with the top surface of wall 107. It is apparent that by tightening the nut 110 on the threaded extremity of post 102 the assembly may be tightened upon wall 107 and thereby supported. It may be noted that as shown in Fig. 5, the conductors 79 and 80 pass through the space formed around post 102 by the casing 105 and flange 109 and extend outwardly through an opening 111 in casing 105.

The inlet conduit 103 extends upwardly and connects with a horizontal conduit 112 formed in the bottom of base member 6. The left hand end of conduit 112 is adapted to be placed in communication with conduit 95 leading to inlet port 90 through a control valve or faucet structure 10. Thus there is a boss 113 extending upwardly from the top surface of member 6 (see Fig. 1) and having a bore 114 intersecting passage 95 and extending beyond this passage. Boss 113 is externally threaded at its end for the accommodation of a gland nut 115. Fitted within bore 114 is a tubular valve body 116 internally threaded in its upper portion, its lower edge resting on a sealing washer 117, which surrounds an opening 118 extending between passage 112 and the interior of body 116. Valve body 116 has a plurality of radial apertures 120 arranged at such a height as to align with conduit 95. In this way it is assured that the interior of valve body 116 is in communication with conduit 95 regardless of the angular position of body 116 in boss 113. Thus with the valve open, water can pass from passage 112 through opening 118 into body 116 and thence through one or more apertures 120 into conduit 95.

A valve closure 119, in the form of a cylindrical member, has a lower face adapted to seal against washer 117, and is loosely mounted on the ball end 121 of a valve stem 122. Valve stem 122 has an enlarged threaded portion 123 engaging the threads in body 116. These threads have a coarse pitch, so that rotation of stem 122 through substantially less than a complete revolution suffices to lift closure 119 a suitable distance above washer 117. Stem 122 may be packed by suitable material 124 disposed in gland nut 115 and may have a handle 125 secured thereon for convenient manipulation.

It may be desirable to restrict the amount of liquid that can flow into inlet passage 95 even when valve 10 is fully opened. For this purpose the left hand end portion 126 of passage 112 is provided with screw threads extending beyond opening 118. A headless screw 127 is positioned in this threaded portion 126 which is adapted to close opening 118. By adjusting the position of screw 127 the effective area of opening 118 may be altered, whereby the maximum flow of water from passage 112 to passage 95 and thence into the inter electrode space 4 may be controlled; and accordingly the degree of heating may be regulated. A headed screw 128 serves to close the end of passage 112 in a fluid tight manner.

The spout 8 is intended to discharge a mixture

of water heated by passage between the electrodes, and water directly from inlet 7, whereby by appropriate independent regulation of the faucets 8, 10, water of a desired temperature may be obtained. Thus, a passage 129 extends to the right from inlet 103 (Fig. 1) and has an upward extension for supplying water into the interior of valve body 130, of a valve 9, the general structure of which is the same as that of valve 10, for controlling the flow of hot water. Valve 9 has a handle 132 for convenient manipulation.

Valve 9 is adapted to pass water into conduit 133 which communicates directly with spout 8 (Fig. 2) and is separated by wall 134 from the hot water outlet 99.

It may sometimes happen that the valve or faucet 10 controlling admission of water to be heated is not tightly closed, so that a small amount of water would be admitted into the annular spaces 4 and 5 and there heated. This would result in substantial waste of current. To prevent this, adjacent the lower edge of electrode 21 a restricted bypass or port 135 (Fig. 1) is provided between the inlet port 90 and annular space 15 in the bottom of body 3. As shown port 135 is formed by a notch in the bottom of electrode 2, but it could obviously be formed equally well in body 3. This bypass 135 permits a small amount of water passing valve 10, due to leakage or otherwise to pass directly to spout 8 without entering space 5. However, it has no material effect upon the quantity of water passing into this space to be heated when valve 10 is purposely opened.

The mode of operation of the device will be apparent from the foregoing. Upon manipulating either of the handles 125 and 132 or both to open their associated valves 10, 9, water is discharged through spout 8, the relative extent of opening of the valves controlling the proportion of the water that is heated and hence the temperature of the water delivered. Due to the fact that the flow of liquid between the electrodes is downward, any tendency for sediment to collect is obviated. Foreign material or dirt is washed out by the stream.

The device is not restricted to use as an instantaneous heater of liquid, but by appropriate modification of the liquid connections may be used to heat or vaporize liquid as desired, either continuously or in varying amounts. Such a heater is shown in Figs. 17, 18, 19 and 20.

This heater comprises a body 150 which is substantially identical with the body 3 of the first described form and encloses a pair of spaced concentric electrodes arranged in the same manner. Electrical energy is supplied to these electrodes by leads 151 and 152 leading to terminal collars 153 and 154 carried by cover member 155, all as before.

However, instead of a supporting base 6, body 150 is provided with a simple closure member 156 on its lower end and is intended to be supported in any convenient manner, as for example by the pipes which conduct fluid to and from the heater.

As clearly shown in Fig. 20, cover member 155 has a central hub 158 for threadedly receiving stud 57 by means of which the upper and lower covers 155 and 156 are clamped to the body 150. Cover 156 has a radially extending threaded boss 159 having a port 160 intersected by a port 161. Port 161 terminates in an enlarged space 162 for receiving boss 91. Inlet pipe 163 for the liquid to be heated is secured by a conventional

connection to boss 159 in a fluid tight manner and thereby communicates with inlet port 90 of body 150. Cover 156 has a similar space 164 (see Fig. 18) for receiving boss 161 through which extends a discharge port. A downwardly extending threaded boss 165 has a port 166 for cooperating with port 98. A discharge pipe 167 is threadedly connected to boss 165.

As a means of precisely regulating the inflow of liquid through port 161, a cone pointed screw 168 is provided. This screw is threadedly engaged in boss 168 formed on boss 159 and having a threaded portion axially aligned with port 161. By adjusting the axial position of screw 168 the effective opening of port 161 can be altered. A closure cap 171 is threadedly attached to the exterior of boss 165.

For conveniently controlling the flow of liquid to the heater within the limit set by adjusting screw 168, a valve 172 (Fig. 17) is provided in inlet conduit 163.

What is claimed is:

1. The method of electric heating which comprises passing an arc through vaporized liquid disposed between electrodes presenting active surfaces sufficiently close to produce heating by atomic breakdown, said electrodes being permanently spaced at about .045 inch apart when a source of current at 220 volts is utilized.

2. In a device of the character described, a pair of electrodes so spaced as to form a passageway between them for the accommodation of liquid to be heated, means for supplying liquid to the passageway, including a valve and means forming an outlet from the passageway, there being a continuously open restricted bypass from the valve to said outlet and paralleling said passageway.

3. In a fluid heater, a pair of electrodes forming a substantially vertical passage between them, means forming a second substantially vertical passage adjacent one of the electrodes, means for supplying liquid to said second passage adjacent the bottom thereof, means for permitting liquid to flow from the second passage to the first passage at the top of said passages, means for passing a current through liquid between said electrodes, means forming an outlet from the bottom of the first passage, and means forming a restricted bypass opening between the bottoms of said passage.

4. In a fluid heater, a pair of electrodes so spaced as to form a passage between them for the accommodation of liquid to be heated, means for supplying liquid to the passage including a valve, means forming an outlet from the passage, and means independent of the valve, forming a restricted port between the supply and the outlet, whereby a limited quantity of liquid passing the valve will enter the outlet without entering the passage.

5. In a water heater, a body having a closed cavity, electrodes within said cavity defining a space for the passage of water, said water in said space being adapted to be heated by the passage of current between said electrodes, a base for supporting the body, said base having a water inlet as well as a discharge spout, means for passing water from the inlet to the interelectrode space, means for passing water from said space to said spout, means in said base for passing water directly from the inlet to the spout, and means for independently controlling the passage of water through said space to the spout and directly to the spout.

6. In a water heater, a generally cylindrical body with an enclosed circular cavity, a pair of circular electrodes disposed one within the other coaxially in said cavity and defining a pair of annular spaces, the outer of said spaces being between the body and the outside electrode, the other space being between the electrodes, means whereby said spaces are in communication, a base member generally conforming with the shape of the body for supporting the body, said base having passageways forming a water inlet as well as a discharge spout, means forming a passage from said inlet to one of said annular spaces, means forming an outlet from the other of said spaces to said spout, means forming a passage from said inlet directly to said spout, and valve means for independently controlling said passages.

7. In a water heater, a generally cylindrical body having an enclosed circular cavity, a pair of circular nested electrodes mounted coaxially in said cavity and defining a pair of vertical annular spaces, one of said spaces being between the electrodes, the other space being between the outer electrode and the wall of the cavity, means whereby said spaces are in communication at their upper ends, a base member on which the body is supported, said base having passageways forming a water inlet as well as a discharge spout, means forming a passage from said inlet to the bottom of said outer space, a valve for controlling said passage, means forming a passage from the bottom of said inner space to said spout, a passage from aid inlet directly to said spout, and a valve for controlling said last mentioned passage.

8. In an electric heater, a pair of coaxial cylindrical electrodes defining a vertical annular space between them, means for passing a current through liquid between said electrodes, a base supporting both of said electrodes at the bottom, and a spout carried by the base, said base having a passageway between the lower end of said annular space and the spout, said base having another passageway for passing liquid upwardly into the upper part of said annular space.

9. In an electrical heater, a base member having inlet and outlet passages, a pair of concentric inner and outer electrodes forming a vertical annular space between them, a central tapered supporting post cooperating with a corresponding tapered aperture in the inner electrode, and supported on the base, and means for maintaining the outer electrode in coaxial position with respect to the inner electrode and disposed adjacent the top of the electrodes, said inlet and outlet passages communicating with opposite ends of the annular space.

10. In an electrical heater, a base member having inlet and outlet passages, a support made from insulation material and disposed on the base, said support having a tapered central post, an inner cylindrical electrode telescoped over said post, an outer cylindrical electrode defining a vertical annular space with said inner electrode, and having a lower edge disposed on said support, a spacer member of insulation material disposed between the upper ends of said electrodes, and a cover member of insulation material disposed over the electrodes.

11. In an electrical heater, a base member having inlet and outlet passages, a support made from insulation material and disposed on the base, said support having a tapered central post, an inner cylindrical electrode telescoped over said

post, an outer cylindrical electrode defining a vertical annular space with said inner electrode, and having a lower edge disposed on said support, a spacer member of insulation material disposed between the upper ends of said electrodes, said support having an annular portion extending upwardly around and spaced from the outer electrode, and a cover member of insulation material disposed over the electrodes and in fluid tight relation to said annular portion.

12. In an electrical heater, a base member having inlet and outlet passages, a support made from insulation material and disposed on the base, said support having a central post, an inner cylindrical electrode disposed on said post, an outer cylindrical electrode defining a vertical annular space with said inner electrode, and having a lower edge disposed on said support, a spacer member of insulation material disposed between the upper ends of said electrodes, said support having an annular portion extending upwardly around and spaced from the outer electrode, and a cover member of insulation material disposed over the electrodes and in fluid tight relation to said annular portion, said inlet passage communicating with the space around the outer electrode, and said outlet passage communicating with the lower portion of the annular space between the electrodes.

13. In an electrical heater, a base member having inlet and outlet passages, a pair of concentric inner and outer electrodes forming a vertical annular space between them, and means for maintaining said electrodes in true concentric relation and for supporting said electrodes on the base, said means having an annular portion spaced from and surrounding the outer electrode, said inlet passage communicating with the space around the outer electrode, and said outlet passage communicating with the lower portion of the annular space between the electrodes.

14. In an electrical heater, a base member having inlet and outlet passages, a pair of concentric inner and outer electrodes forming a vertical annular space between them, and means for maintaining said electrodes in true concentric relation and for supporting said electrodes on the base, said means having an annular portion spaced from and surrounding the outer electrode, said inlet passage communicating with the space around the outer electrode, a cover member of insulation material disposed over the annular space and supported by aid of said annular portion of the support, and terminal structures for the electrodes supported by the cover member.

15. In an electrical heater, a base member having inlet and outlet passages, a pair of concentric inner and outer electrodes forming a vertical annular space between them, and means for maintaining said electrodes in true concentric relation and for supporting said electrodes on the base, said means having an annular portion spaced from and surrounding the outer electrode, said inlet passage communicating with the space around the outer electrode, a cover member of insulation material disposed over the annular space and supported by aid of said annular portion of the support, and terminal structures for the electrodes supported by the cover member, each of said terminal structures including a metal ring in electrical connection with the respective electrodes, the rings being concentric, as well as an ear extending from the ring.

16. In an electrical heater, a base member having inlet and outlet passages, a pair of concentric

inner and outer electrodes forming a vertical annular space between them, and means for maintaining said electrodes in true concentric relation and for supporting said electrodes on the base, said means having an annular portion spaced from and surrounding the outer electrode, said inlet passage communicating with the space around the outer electrode, a cover member of

5 insulation material disposed over the annular space and supported by aid of said annular portion of the support, and terminal structures for the electrodes, each having a conductor receiving member supported respectively in recesses in the cover.
